DOUBLE PEDESTAL DESK OR SIMILAR ARTICLE

Charles M. Abrahamson, Aurora, and Pehr J. Anderson,
St. Charles, Ill., assignors to All-Steel Equipment Inc.,
Aurora, Ill., a corporation of Illinois

Filed July 5, 1960, Ser. No. 61,231

Term of patent 14 years

(Cl. D33—7)

Fig. 1.

Fig. 2.

Fig. 3.

FIGURE 1 is a front perspective view of a double pedestal desk, showing our new design;

FIGURE 2 is a rear perspective view of the same; and

FIGURE 3 is a fragmentary perspective view of the leg structure.

The dominant features of the design reside in the portions shown in full lines in the drawing and are characterized by legs of angular cross section which are recessed into the side panels and spaced from the adjacent edges of the panel, in combination with the framed panels on the front and rear faces of the pedestals, substantially as shown.

The side of the desk not shown and the undisclosed inner face of one drawer pedestal are respectively the same in appearance as the side shown and the disclosed inner pedestal face.

We claim:

The ornamental design for a double pedestal desk or similar article, substantially as shown and described.
